UNITED STATES PATENT OFFICE

LOUIS W. MEYERS, OF CHICAGO, ILLINOIS

BOOKBINDING MACHINE

Application filed May 10, 1928. Serial No. 276,773.

This invention relates to machines for use in the binding and backing of books or the like.

An object of the invention is to provide a binding machine having a vise comprised of a stationary and a movable jaw, foot-operated means being provided to quickly move the movable jaw into engagement with an object to be held between the jaws, whence 10 the vise may be tightened by hand in the usual manner.

Another object is to provide a device of the character referred to provided with means to automatically return the movable 15 jaw to its open or normal position when not in use.

A further object is to provide a device of the character referred to having the usual vise screw and hand wheel secured thereto, 20 a loosely mounted nut being carried by the screw between the hand wheel and the movable jaw of the vise, whereby movement of the hand wheel will cause the nut to engage the movable jaw and retain said jaw in engagement with an object placed in the vise. 25

Other objects and advantages will become apparent during the course of the following description.

In the drawings I have shown several embodiments of my invention. In this showing:

Figure 1 is a side elevation,

Figure 2 is a central vertical section with the lower parts broken away,

Figure 3 is a plan view,

Figure 4 is a front elevation, and,

Figure 5 is a central vertical section of a modified form of the invention with the lower parts broken away.

Referring to the drawings the numeral 10 40 designates the frame of the machine adapted to receive a suitable bed 11. A vise is mounted on the bed 11 and consists of a stationary jaw 12, preferably formed integral with the bed and having a vise plate 13 secured thereon, and a movable jaw 14 having a vise plate 15 secured thereon. As shown in Figures 1 to 4 of the drawings the jaw members 12 and 14 are inclined with respect to the horizontal plane of the device, the member 12 being 50 slightly higher for a purpose to be described.

Preferably formed integral with the jaw 12 and on each side thereof, and arranged at an angle to the bed, is a guide arm 16. As shown in Figures 1 and 4, the sides of the jaw member 14 extend outwardly of the bed and have a downwardly projecting portion 17, which 55 engages the guide arm 16. A suitable plate 18 engages the bottom of the arm 16 and portions 17, and is secured by bolts 19 or the like, to the portions 17 whereby a channel is formed surrounding the arm 16. It will readily be seen that the jaw member 14 is mounted for sliding movement on the guide arms 16. Depending from the jaw 14 and substantially centrally thereof, is a pair of 60 spaced ears 20, preferably formed integral with the jaw, suitable openings being provided adjacent the lower extremities of the ears to receive a pin or shaft 21. A pair of rollers 22 are mounted on the shaft 21 outwardly of the ears 20 and these rollers are held on the shaft by cotter pins or the like 65 70 75 23.

The frame 10 is provided on its sides and substantially centrally thereof with preferably integral arms 24, carrying suitable journal boxes 25 in which are rigidly secured a bearing rod 26, by means of set screws 27 or the like, threaded into said journal boxes and engaging said rod. A relatively large lever 28, having a forwardly extending portion 29, is pivotally mounted on the rod 26. As shown in Figure 4, the upper extremity of the lever 28 is bifurcated and the pivotal connection with the rod 26 is made through the arms 30. Set screws 31 or the like extend through the arms 30 into suitable grooves in the rod 26 whereby the lever may pivot with respect to the rod but is incapable of longitudinal movement thereon, as will be understood. The arms 30 extend upwardly a substantial distance above the shaft 21 and each arm is adapted to engage one of the rollers 22. A foot pedal 32 is arranged on the forward extremity of the lever. It will be apparent that when the lever is depressed the arms 30 thereof will engage the rollers 22 and slide the movable jaw into engagement with the stationary jaw. If the lever is released the movable jaw will return to its normal or open position by gravity because of its inclined 80 85 90 95 100 plane.

relation with the stationary jaw. A vise screw 33, mounted in a suitable bearing 34 and carrying the usual hand wheel 36, is arranged rearwardly of the movable jaw 14. 5 As shown in Figure 2, a recess is formed in the movable jaw and the inner extremity of the screw is adapted to extend into this recess. Mounted on the screw 33 and provided with threads in which said screw operates, is 10 a preferably rectangular nut or block 37, and a pair of relatively wide side plates 38 are secured to the jaw member 14, by bolts 39 or the like. These plates prevent the nut 37 from turning and they extend rearwardly a 15 sufficient distance to prevent rotation of the nut when the jaw 14 is in its forward or closed position.

In the modified form of the device shown in Figure 5, the jaw members 40 and 41 are arranged in the same horizontal plane. Movement of the lever 42 will slide the jaw members 41 forwardly as in the preferred form of the invention. Means are provided for returning the members 41 to open position. An 25 eye bolt 43 or the like is threaded into the rear of the members 41 and a suitable cable 44 is secured in said eye and provided at its opposite extremity with a weight 45. This cable is guided on a pulley 46 mounted on the 30 bed and it will be apparent that positive means are provided for returning the jaw 41 to its open position.

The operation of the device is as follows:

When it is desired to place a book in the 35 machine, the book is placed in proper position against the stationary jaw member 12. The foot lever 29 is then depressed and the movable jaw member 14 is forced into engagement with the book. The hand wheel may then be 40 turned rapidly until the nut 37 engages the rear of the member 14 and the jaws may be tightened as much as necessary. The foot lever is then released and the book is firmly held in the vise.

45 Sometimes the work to be done on a book is so slight as to make it unnecessary to screw the block 37 into position and the work may be performed while the foot lever holds the book in position. When this work is completed the 50 foot lever may be released and the jaw 14 will return to open position as hereinbefore explained.

It will be apparent that I have provided a device which will quickly and efficiently engage and hold a book of substantially any thickness. The device is described for use in connection with books to be bound, but it is obvious that other uses may be made thereof.

It is to be understood that the forms of my 60 invention herewith shown and described are to be taken as preferred examples of the same and that various changes in the shape, size, and arrangement of parts may be resorted to without departing from the spirit of my invention or the scope of the subjoined claims.

I claim:

1. In a device of the character described, a supporting frame, a stationary jaw member carried by said frame, a movable jaw member slidably mounted on said frame, a screw journaled in said frame and adapted to project into an opening in said movable member, a nut loosely mounted on said screw, rotation of said screw being adapted to force said nut into engagement with said movable member, means carried by said movable member to prevent rotation of said nut, and foot-operated means carried by said frame for moving said movable member into engagement with said stationary member. 70

2. A device constructed in accordance with claim 1 wherein said last mentioned means includes projections depending from said movable member, a pin carried by said projections, rollers mounted on said pin, and a lever pivotally mounted on said frame, said lever being adapted to engage said rollers. 75

3. In a device of the character described, a supporting frame, a stationary jaw member carried by said frame, a movable jaw member slidably mounted on said frame, a screw journaled in said frame, and adapted to project into an opening in said movable member, a nut loosely mounted on said screw, rotation of said screw being adapted to force said nut into engagement with said movable member, a pair of spaced plates carried by and projecting from said movable member and adapted to prevent rotation of said nut, and foot-operated means for moving said movable member into engagement with said stationary members. 90

4. A device constructed in accordance with claim 3, wherein said means comprises projections depending from said movable member, a pin carried by said projections, rollers mounted on said pin, and a lever pivotally mounted on said frame, said lever being adapted to engage said rollers. 105

In testimony whereof I affix my signature. 110
LOUIS W. MEYERS.
